TOOTHBUSH

John E. O'Donnell, Yakima, Wash.

Application August 27, 1932. Serial No. 630,641

4 Claims. (Cl. 15—188)

My invention relates to tooth brushes, and more particularly to those of the type made of rubber, or similar soft flexible material. While the invention is hereinafter described as embodying rubber bristles of cup-like form which are split, it is to be noted that the bristles may each consist of a curved or semi-circular rubber-like member instead of each bristle unit being in the form of a split cup.

10 One object of my invention is to provide bristles of the character referred to which in use more effectively reach and massage the more remote portions of the teeth and gums instead of the rubbing action being confined mainly to the more convex or protruding portions of the teeth.

15 Another object of my invention is to provide a brush wherein the dentifrice will be forced into the recesses between the teeth and at the base thereof, and wherein it will be retained at those points where it may be most effectively utilized, with a minimum of waste.

20 Another object of my invention is to provide a bristle of such form that irritation of the tissues thereby will be minimized.

25 Still another object of my invention is to provide a brush of generally improved form.

In the accompanying drawing, Figure 1 shows a face view of the brush; Fig. 2 is a side elevational view; Fig. 3 is a longitudinal sectional view, 30 on an enlarged scale; Fig. 4 shows a brush positioned against the sides of teeth being cleaned, looking at the bottom of the teeth; Fig. 5 is a view showing a bristle and a tooth, looking at the side of the tooth, and Fig. 6 shows a modification 35 of the invention.

The brush handle 6 may be of bone, metal, or suitable molded material. What I term the bristles 7 are formed of rubber or material having similar characteristics in the way of flexibility 40 and softness. The bristles 7 are of cup-like form, fastened to the handle 6 by screw studs 8 whose heads are molded in the bases of the bristles 7, but it will be understood that the bristles may be secured to the handle in any other suitable manner.

45 The cups are shown as of approximately circular form in cross section, but it will be understood that they may be oval or of any other suitable form. The walls of the cups are split at 9 to permit the half portions thereof to spread when pressed against the teeth, as shown in Fig. 4. The flexibility of the half portions of the cup is determined by the thickness of the bottom wall or base of the cup, as well as the wall thickness 50 of the half portions, and these dimensions

can be varied to produce bristles having a desired degree of flexibility.

The half portions of the bristles are cut away or beveled at 10 so that there is no abrupt or sharp corners present to damage the gums of the user. 60

In using the brush, a suitable dentifrice may be introduced into the bristles, whereupon they are applied to the teeth and the brush handle manipulated in the usual manner. The dentifrice will, of course, be in the most favorable position 65 to be utilized by the inner or working faces of the bristles, so that there is little waste of the dentifrice, and furthermore, it will be forced between the teeth by pumping action of the bristles, thereby replacing any debris and performing its sterilizing function. The inner or working surfaces of the cups may be fluted or knurled in order to increase their effectiveness in carrying dentifrice to and cleansing the teeth. 70

The flexibility of the bristle sections or cup walls will prevent them from penetrating and irritating the soft tissues which surround the teeth, and the lips of the cups can be pushed under the free margins of the gums at the bases of the teeth, and will remove foreign matter therefrom 75 and cleanse the necks of the teeth which lie under the free margins of the gums and sulci of the canines, bicuspids and molars. 80

In manipulating the brush as shown in Figs. 4 and 5, for example, it will be seen that the higher 85 or more convex portions of the teeth will not be submitted to pronounced rubbing or abrading action, as is the case with various types of brushes heretofore employed. The more convex areas of the teeth will require little or no rubbing, since 90 they are kept clean through contact with the lips and the tongue, and also through the chewing of hard food. It will be seen, therefore, that the design of my brush is such that its cleansing and massaging action will be confined principally 95 to those portions of the teeth and gums that are not readily accessible by rubber brushes which are of unsplit cup form and which do not have the great flexibility of the bristles as shown in the drawing. 100

Even in the case of the ordinary bristle brush, the cleansing action is confined largely to the more convex areas of the teeth.

As heretofore indicated, I do not confine myself 105 to rubber brushes of split cup form, as it will be obvious that rubber bristles which are simply curved about their longitudinal axes may be employed to secure various of the results above pointed out. Also the rubber brushes may be of semi-circular form in cross section, instead of 110

cup-like form, as shown in Fig. 6 wherein the brush elements 12 are fastened to the handle or holder 13. These brush elements 12 will each function in substantially the same manner as does 5 each of the divided portions of the cups 7.

The curvature of the bristles causes the outer edges thereof to be placed under some tension when the bristles are flexed, so that the said outer edges will tend to cling to the surface being 10 brushed or massaged, and to conform to the contour of said surface. This feature is of utility in forcing the lips or outer edges of the bristles under the free margins of the gums. Obviously, those portions of the working surfaces of the cup 15 removed from the outer edges thereof are not under so great tension and will not exert so great rubbing action on the convex surface of the teeth.

I claim as my invention:—

1. The combination with a holder, of a brush member of flexible material connected at its inner 20 end to said member and being of semi-conical form about an axis extending outwardly from said

holder, the said member being of tapering thickness toward its outer end.

2. The combination with a holder, of a brush member of flexible material connected at its inner 8 end to said member and being of semi-conical form about an axis extending outwardly from said holder, the inner wall of said member sloping from its inner end toward its outer end and away from said axis.

3. The combination with a holder, of a brush 85 member of flexible material having a cone-shaped recess and a solid base secured to said holder, the cone-shaped recess being split toward the base to divide it into semi-circular halves.

4. The combination with a holder, of a brush 90 member of flexible material having a thickened base secured to the holder and being of semi-conical form about an axis extending outwardly from the holder, the brush member being of tapering wall thickness toward its outer end. 95

JOHN H. O'DONNELL.
